UNITED STATES PATENT OFFICE

HYMAN RUBIN, OF ROXBURY, MASSACHUSETTS

STORE-FRONT CONSTRUCTION

Application filed March 1, 1929. Serial No. 343,642.

This invention aims to provide an improved store front construction and in the illustrative embodiment of the invention shown in the accompanying drawings:

5 Fig. 1 is a front elevation of a portion of the store front construction embodying the invention showing various types of joints used therein with portions broken away to save space in the drawings;

10 Fig. 2 is a section taken on line 2—2 of Fig. 1;

Fig. 3 is a detail horizontal section through one side of a modified form of sash;

15 Fig. 4 is a detail horizontal section taken for example on the line 4—4 of Fig. 1, showing a modified arrangement of division bar;

Fig. 5 is a section taken along the line 5—5 of Fig. 3;

20 Fig. 6 is a detail section on line 6—6 of Fig. 2; and

Fig. 7 is a section through a modified form of corner bar.

In the particular embodiment of the invention selected for purposes of illustration 25 and shown in the drawings, the present store front construction comprises a frame including a jamb 1 for supporting various panels or glass sections 3 such as usually compose a store front. The store front as represented

30 herein is desirably of the type composed of metal frames for holding the glass panels or windows 3, and the first of these frames, one side of which is indicated in section at 5 (Fig. 2), is a window sash; next to the sash section 35 5 I have shown a division bar 7 for sealing or closing the space between adjacent sections of glass or panels; next follows a corner bar construction 9; and finally a reverse corner bar construction 11 is shown.

40 The corner bar construction 9 herein represents a corner of approximately ninety degrees, and consequently the reverse corner bar construction 11 will describe a ninety degree angle, but it is to be understood that the 45 invention is not limited to any specific angle, as will be clearly obvious.

The sash 5 preferably embodies in its construction an inner strip 13 arranged to fit nicely into a shoulder or seat 15 formed in 50 the side jamb 1, said inner strip being de-

sirably composed of sheet metal, and bent to form a rear seating wall 17 and a side seating wall 19. The wall member 17 has a forwardly projecting flange 21 perforated at 22 for ventilation, said flange 21 terminating in a 55 marginal lip 23 against which the window glass section 3 is arranged to seat. The sash section 5 also includes a front strip 6 desirably formed from a separate strip of metal with its outer face shaped to conform with 60 any of the usual forms of moldings, that herein shown being reversely curved and ornamental in appearance as it is the most conspicuous portion of the sash.

One marginal portion of the strip 6 is extended laterally at 25 to form a flange which engages the panel 3 in opposed relation to the flange 23 of the inner strip 13. The other edge of the strip 6 is bent at 26 to form a flange 27 along which are provided ventilating perforations 28 and the edge of this flange is bent rearwardly to form a lip 29 which slips behind the wall 19 of the inner strip 13. The wall 19 is slightly offset at 30 sufficiently to provide space for the lip 29. 70 The front strip 6 may be secured in place in any appropriate manner, as for example by a screw 31 extending through a perforation in the reversely curved wall of said strip and into the side jamb 1. The inner members of 75 said strip may also be secured to said jamb, for example by means such for example as a screw 33 passing through the rear wall 17.

Where the store front is quite wide it is often desirable to make the glass thereof in 80 sections for convenience in handling, and in such cases adjoining panels may be secured together by means of a division bar, as indicated at 7 (Figs. 1 and 2).

In the present example the division bar 85 comprises an outer strip 35 composed of sheet metal bent longitudinally to form ribs 37 and 38, said ribs being substantially parallel to each other although not limited thereto. These ribs extend inwardly from said outer strip desirably to points substantially within the inner face of the panels 3 to provide lateral stiffness to said strip. Said division bar also includes flanges 39 and 40 extending 90 in opposite directions from their respective 95

ribs 37 and 38 but lying substantially in the same plane. The flanges 39 and 40 are arranged to engage the outer marginal portions 41 of adjacent panels 3, the ribs 37 and 38 of said bar passing inwardly through a gap 43 formed between said adjacent panels. Between the ribs 37 and 38 and secured rigidly to said division bar is a screw 45 having a flat-sided head 47 which is inserted in an elongated perforation 49 formed centrally of said division bar between the ribs 37 and 38 and said head is securely riveted to said division bar to maintain said screw with its axis approximately at right angles to the outer face of said bar or the plane of said flanges 39 and 40. The metal of the division bar 7 surrounding the perforation 49 is slightly countersunk to receive the riveted or enlarged metal of the head during the riveting operation, thereby providing a shoulder for holding said screw and leaving the outer surface of the head flush or conforming with the outer face of said bar. Over the outer face of said division bar I desirably provide a thin sheet of finishing material 51, such for example as copper, which closes the creases 53 formed by the ribs 37 and 38 and gives to the bar a pleasing appearance or finish, likewise preventing the exposure of the material composing the division bar to the elements to cause it to rust.

Associated with the outer strip or said division bar 7 is an inner strip 55, desirably of channel form, having a base 57 and side walls 58 which latter terminate at their rims in outwardly bent flanges 59. The outer edges of the flanges 59 are desirably reversely bent inwardly at 60 to form flanges 61, which latter terminate at points in close proximity to the ribs 37 and 38, said flanges and ribs cooperating to position the inner and outer strips relatively to each other. The flanges 59 and 61 produce double strips or lips which engage the edges of the panels 3 opposite the flanges 39 and 40 and by being double provide a more rigid and durable bar structure. The base 57 of the inner strip is perforated at 63 and through this perforation extends the screw 45. A nut 65 is arranged in screw-threaded engagement with the screw 45, said nut having a reduced tapered shank 67 which fits said perforation, and when the nut 65 is screwed up tightly said tapered shank enters said perforation and centers the inner strip properly with relation to the outer strip, and upon applying sufficient pressure to said nut the flanges 61, 39 and 40 will firmly grip the adjacent edges of the panels 3 and maintain a moisture-tight joint.

69 The corner bar 9, hereinbefore referred to, desirably comprises an outer strip 69, including flanges 71, shown as forming an angle of approximately ninety degrees (although it is not limited thereto), and engaging marginal portions of the adjacent panels 3 forming

the corner of the store front. A screw 73 similar to the screw 45 of the division bar 7 is arranged in said corner bar with its axis approximately bisecting the angle described by the inner faces of the flanges 71. The head of said screw is secured to the outer strip of said corner bar in substantially the same manner as described in connection with the screw 45 of said division bar. An inner strip 75 is provided for said corner bar and desirably comprises a channel-like section 77 having outwardly diverging flanged sides 78 terminating in flanges 79 describing the same angle as that described by the flanges 71 and engaging the inner marginal portions of the adjacent panels 3 forming said corner. The screw 73 extends through a suitable perforation formed in the base 81 of said member 75 and a nut 83 is screwed up against said base and draws the inner strip 75 firmly against the panels 3, thus securely clamping said inner and outer corner strips together against said panels.

70 It is to be understood that the present invention is not limited to corners of ninety degrees but may be varied to suit the particular circumstances of the case.

75 The reverse corner bar 11 is composed of an outer strip 85 having side flanges 87, herein forming an angle of ninety degrees between the outer faces thereof. A screw 89 is rigidly secured at the intersection of the flanges 87, the stem of said screw extending inwardly for engagement with an inner strip 91, which latter is of substantially channel form having a base 93 and side members 95 being divergently arranged and provided with offsets 96 which help to stiffen said sides and may serve as shoulders in a reinforcing bar when such is used, as will be hereinafter stated. The edges of the side members 95 desirably terminate in double flanges 97 so angularly disposed with relation to each other as to conform to the inner marginal faces 99 of adjacent panels 3 and in opposed relation to the flanges 87 of said outer strip. A nut 101 has screw-threaded engagement with the screw 89 and is arranged to be turned on said screw to draw the outer strip 85 and the inner strip 91 toward each other firmly to grip the two panels 3 and maintain the latter in their desired angular relation and form a moisture or rain proof corner joint.

80 If desired all of the exposed parts or the various bars, when composed of steel or iron, may be covered with thin sheet copper or other suitable finishing material in order to provide a more pleasing appearance.

85 It is desirable at times to provide a reinforcing bar for the various inner strips of the several bars, and an example of such an arrangement is shown in Fig. 4, in which 103 is a reinforcing bar used in connection with a division bar, substantially similar to 130

that shown at 7 in Fig. 2. The use of such a reinforcing bar requires little if any change in the forms of the associated parts except in the case of the inner strip 105, which instead of employing angularly disposed offsets in the side members 58, as shown in Fig. 2, is provided with substantially square offsets 107 or, as shown at 96 in Fig. 2, against which the inner edges 109 of the side elements 10 of said bar 103 may seat. A screw 111 considerably longer than the screw 45 of the foregoing construction will however be required in order to extend through the base 113 of said reinforcing channel bar, and a nut 115 is provided to seat against said closed end, and upon being screwed up will cause the member 103, the inner strip 105 and the outer bar 117 to be firmly drawn together against the marginal portions of the panel 3, and so form a tight moisture-proof joint.

In Fig. 6 I have shown in a section taken at substantially right angles to that shown in Fig. 2, the screw 45 and the elongated slot into which the flat-sided head 47 of the screw 25 is riveted, clearly indicating that the outer end 46 of the head is finished flush with the outer face of the division bar.

In the previous examples the several bars are shown as composed of body members of 30 sheet steel or other strong material, but these strips are veneered or covered with a finishing material of a more expensive and more durable nature such as copper, thus making the construction slightly less expensive although stronger than would be the case were said reinforcing bars composed entirely of copper or similar material. Furthermore the screws for securing the several sections of the bars together, as hereinbefore 40 scribed, are completely concealed beneath the finishing material. It is to be understood however that the invention is not limited to that method employed in the preceding figures, but they may be wholly composed of the 45 more expensive material, and in Fig. 7 I have shown a form of corner bar in which the outer strip 119 is similar in form to the strip shown in said Fig. 2 and has a screw 121 formed of like material with a flattened head 123 inserted in a suitably formed perforation 125 in the corner of said angle bar and headed over as shown at 127 so as to conform nicely with the beaded corner of said strip 119.

In Figs. 3 and 5 I have illustrated a slightly different arrangement of sash strips from that shown in Fig. 2. In this case the outer strip 129 corresponding to the part 6 in Fig. 2 is not provided with the marginal flange 55 but terminates by abutting at 131 against the metal covering 133 of the side jamb 135, and to prevent this edge of said strip 129 from slipping past the abutting edge 137 of the wall 139 of the inner strip 141 during 60 assembling, a plurality of elongated abut-

ments 143 are provided in the edge of said wall 139, these abutments being of sufficient depth to insure against the slipping of said strip 129 past the edge of the wall 139 when the latter is being screwed in place against the panel 3'. Desirably the abutments 143 are differently spaced, as shown most clearly in Fig. 5, so as to permit the use of outer strips 129 of varying lengths, the abutting ends of said strips meeting at the abutments 143.

This invention is not limited to the particular embodiments shown.

Claims:

1. In a store front construction, a division bar comprising an outer strip having longitudinal inturned parallel ribs each doubled back upon itself and terminating in lateral opposed flanges, a screw secured to said division bar between said ribs, and an inner strip provided with an opening aligning with said screw and means for engaging said screw for drawing said inner and outer strips together.

2. In a store front construction, a division bar comprising an outer strip having longitudinal, inturned, parallel ribs each turned back upon itself, flanges extending outwardly from the outer edges of said turned back portion and arranged in alignment one with the other, an inner strip provided with flanges corresponding to and cooperating with the flanges of said outer strip, and means to draw the flanges of said inner and outer strips toward each other to clamp a panel between them.

3. In a store front construction, a division bar comprising an outer strip having longitudinal, inturned, parallel ribs, flanges extending outwardly from said ribs in alignment one with the other, an inner strip composed of sheet material having its marginal portions bent outward in a common plane, thence inwardly to points inside of the first mentioned bends to points adjacent the outer faces of said longitudinal inturned ribs to cooperate with said ribs in positioning said inner and outer strips and constituting flanges, and means to draw said inner and outer strips toward each other to cause their respective flanges to grip the edges of panels.

4. In a store front construction, a division bar comprising an outer strip having inturned stiffening ribs each doubled back upon itself, the free edges of said double back portions terminating in flanges extending in opposite directions from said ribs, panels having their marginal portions arranged against the inner faces of said flanges and terminating adjacent to said ribs, an inner strip having flanges approximately parallel with and cooperating with the flanges of said outer strip, and means for drawing said inner and outer flanges toward each other against said panels.

5. In a store front construction, an outer

bar having an elongated perforation extending the long way of said bar, a screw having a flat sided head riveted into said perforation with the stem of said screw turned inward, and an inner bar cooperating with said outer bar and secured thereto by said screw.

6. In a store front construction, an outer bar having an elongated perforation extending the long way centrally of said bar, a screw having an elongated head rigidly riveted into said perforation with its head flush with the outer face of said bar, and a covering of finishing material covering the outer face of said bar and the head of said screw.

15. 7. In a construction of the class described, inner and outer strips each having outwardly extending cooperating flanges, a screw extending from one to the other of said strips said screw having a flat sided head riveted 20 flush with the outer face of said outer strip to prevent rotation thereof, and a nut having a reduced tapered shank extending through said inner strip to draw said strips together.

8. In a construction of the class described, 25 inner and outer strips one of said strips having marginal flanges angularly disposed with respect to each other, a screw rigidly secured to one of said strips with its axis approximately bisecting the angle of said flanges, 30 the bar comprising a channel having diverging sides, the marginal portions of said sides being bent outwardly to form flanges disposed at angles approximately corresponding to the angle described by the flanges of 35 said outer strip, and means cooperating with said screw to force said inner and outer strips toward each other.

9. In a construction of the class described, 40 an outer strip having marginal flanges disposed with respect to each other at an angle approximating at least ninety degrees, a screw having a flat sided head riveted to said strip with the head of said screw approximately flush with the outer face of said strip, 45 an inner strip of channel form having marginal flanges disposed with respect to each other at an angle corresponding to the angle of the marginal flanges of said outer strip, perforations in said inner strip to receive 50 said screw, and a means cooperating with said screw to draw said strips together.

10. In a store front construction, a bar comprising inner and outer strips, one of said strips having longitudinal, spaced stiffening 55 ribs, the other of said strips being channeled to receive the ribs of the outer strip, and cooperating flanges on said strips for engaging opposite faces of adjacent panels and extensions on the flanges of one strip for engaging 60 the other strip relatively to position said strips and forming moisture proof connections therebetween.

11. In a construction of the character described, inner and outer strips, cooperating 65 elements including members, 61, 37 and 38 to

stiffen said strips and to effect alignment of one strip with the other, and cooperating panel engaging flanges on said strips arranged to engage opposite faces of a panel.

12. In a store front construction, a division bar comprising an outer strip having a channel shaped body, the legs of which body extend inwardly between adjacent edges of the panels joined by said bar, said legs being doubled upon themselves and terminating in flanges extending laterally in opposite directions and lying approximately in the plane of the base of said channel, a screw secured in said base and an inner strip having a body opening aligning with said screw, flanges on said body arranged in opposed relation to the flanges of said outer strip, and means for cooperating with said screw to draw the flanges of said inner and outer strips toward each other against opposite faces of said panels.

In testimony whereof, I have signed my name to this specification.
